UNITED STATES PATENT OFFICE.

JOHN A. EITUTIS, OF CHICAGO, ILLINOIS.

AUTOMATIC STOPPING AND STARTING DEVICE FOR PHONOGRAHS.

1,390,682.

Specification of Letters Patent. Patented Sept. 13, 1921.

Application filed December 26, 1919. Serial No. 847,981.

To all whom it may concern:

Be it known that I, JOHN A. EITUTIS, a citizen of the present government of Lithuania, residing at Chicago, in the county of Cook and State of Illinois, have invented new and useful Improvements in Automatic Stopping and Starting Devices for Phonographs, of which the following is a specification.

10 This invention relates to an automatic starting and stopping device for phonographs.

Among the objects of my invention is to provide a device which may be set to automatically stop the turn-table when the playing of the record thereon has ceased, no matter what the diameter of the record may be, and no matter whether the playing continues to the extreme end of the playing 20 groove or not, or to stop the record in advance of that point if desired, and, further, to effect an automatic starting of the turn-table by merely swinging the tone arm into position to place the needle or stylus of the 25 reproducer on the record at the beginning of the playing groove after the device has been set to stop the turn-table at the point desired.

The invention consists further in the matters hereinafter described and more particularly pointed out in the appended claims.

In the accompanying drawings

Figure 1 is a top plan view of the turn-table and tone arm with reproducer, and 35 showing the automatic starting and stopping device of my invention applied in connection therewith and illustrating the parts of said device in one position they assume when holding the turn-table against rotation;

40 Fig. 2 is a side elevational view of said parts, in the same positions as shown in Fig. 1; a portion of the depending marginal flange of the turn-table being broken away to show those parts of my device located 45 beneath the turn-table;

Fig. 3 is an enlarged top plan view of my device and showing the parts thereof in another position for holding the turn-table against rotation;

50 Fig. 4 is a perspective view of one of the arms of said device;

Fig. 5 is an enlarged longitudinal vertical sectional view taken on the indirect line 5—5 of Fig. 3;

55 Fig. 6 is an enlarged top plan view of my device and showing the parts thereof in

positions when the turn-table is free to revolve;

Fig. 7 is a top plan view of the base plate of the device;

Figs. 8 and 9 are top plan views showing the manner in which the frictionally connected arms of the same may be moved at certain times relatively to each other;

Fig. 10 is a form of clamp ring to be hereinafter described; and

Fig. 11 is a top plan view showing a modified form of a detail of construction to be hereinafter described.

In the drawings, a device of my invention 70 is shown applied to a phonograph of the cabinet type having a flat top wall 1, through and above which extends the spindle 2 rotated by a motor contained in the cabinet below said top wall, as usual. Mounted on 75 the spindle, above said top wall, is a flat, circular turn-table 3 having a felted upper surface to support a disk record 4. The tone arm 5 carries at its outer or swinging end a reproducer 6 having a stylus or needle 7 to 80 contact with and travel over the playing face of the record. The opposite end of the tone arm is pivotally mounted in a base member 8 secured to the top wall 1 beyond the turn-table.

To effect an automatic starting of the record by merely swinging the tone arm into position to begin playing and to automatically stop the record when the playing has ceased, no matter what the diameter of the 90 record may be, or at any other point between the beginning and the end of the playing groove, I provide a device constructed as follows:

A flat base plate 9 is secured to the wall 1 95 below the turn-table 3 and between the spindle 2 and base member 8 of the tone arm. On said base plate 9 is mounted a swinging plate 10 pivotally connected with said base plate by a pivot pin 11. Said plate 10 has two arms 12, 13 diverging outward from the pivot pin 11 and each carrying at its outer end a pad 14 of friction material, such as leather, to engage alternately against the marginal flange 15 of the turn-table for stopping and holding the same against rotation. The plate 10 has an integral part 16 projecting rearwardly from the base of said arms, and has its side edges 17, 18 inclined outward and its rear edge 19 105 slightly curved and extending between said side edges. A plunger rod 20 is slidably

mounted on said base plate 9 in guides 21, 21, and carries at its outer end a roller 22 arranged to have rolling contact with the edges 17, 18, and 19 of said projection 16. 5 Said roller is yieldably held in contact with said part 16 by a coiled spring 23 surrounding said rod between the guides 21 and acting constantly to force the roller forward. The rod and roller are in alinement with 10 the center of the pivot pin 11, and when the roller engages the end edge 19 at any place between the ends of said edge, the plate 10 is held in position with its arms 12, 13 out of contact with the turn-table 3, as shown in 15 Fig. 6, thus allowing the turn-table to be moved by the spindle 2. When, however, the plate 10 has been moved to swing the edge 19 beyond the roller 22, the latter is projected forward by the spring 23, and 20 the roller rides up the inclined edge, 17 or 18 as the case may be, and swings the plate 10 quickly into position with one of its arms 12, 13 into engagement with the turn-table to stop the same. When the roller operates 25 against the inclined edge 17, the plate 10 is swung into position as shown in Fig. 1; and when against the other edge 18, the plate 10 is swung into the position shown in Fig. 3.

30 Also pivotally mounted on the base plate 9 is an arm 24 having its inner or swinging end movable in a relatively wide notch or recess 25 in the plate 10 between the arms 12, 13, as shown. At said end, the arm 24 35 has a fixed pin 26 extending downward into an arcuate slot 27 in the base plate 9. Said arm 24 has its other end rigidly secured to the lower end of an upright sleeve 28 pivoted on the base plate 9 by a fixed pin 29 40 rigidly secured to said base plate. The sleeve 28 is held from upward movement by a head on said pin, and is provided below said head with screw threads to receive clamp-nuts 28^a, 28^a and a conical portion 30, 45 with which engages the inner end of a second arm 31, the latter having a conical hole 32 for that purpose. To enable the frictional engagement between the arm 31 and the sleeve 28 to be varied by the clamp nuts 28^a, the apertured end of said arm 31 is 50 split, as at 33, to provide parts which may be spread apart by the clamping action of the nuts 28^a. By the construction described, the arms 24 and 31 will swing about the pivot pin 29 as one arm when there is nothing to hold the inner arm from movement, but when said inner arm 24 is held from movement, as by the pin 26 being 55 against one end of the slot 27, the outer arm 60 may be swung above the sleeve 28 beyond the position at which the inner arm stops. The purpose of allowing said arms to have movement relative to each other at certain times will presently appear. The arm 31 is 65 provided at its outer end with an elongated

slot 34, into which extends a pin 35 carried by the tone arm 5, as shown. To make the device applicable to any phonograph of the type shown, the pin 35 is secured to a split band or ring 36 clamped about the tone arm 70 adjacent the base member 8 by a screw or like fastening member 37. To permit the band to be applied to tone arms of various diameters, as may be found in applying my device to machines of different makes, I 75 will provide a band 38 as shown in Fig. 10. As shown, with said band 38 there is a separate piece 39 having at one end a tongue 40 to be inserted into any one of a plurality of slots 41 in the band 38. At the opposite 80 end of the piece 39 is a lug 42 having screw threads to receive the clamp screw 43. In the particular device shown, the outer end of the arm 31 is offset upward to bring the same within a convenient position for the 85 pin 35 to extend into the slot 34 and not to contact with the top wall 1 of the cabinet. The slot 34 is inclined to the longitudinal axis of the remaining portion of the arm, so that the pin 35 will always engage the edges 90 of the slot 34 in moving in the arc of a circle with the tone arm. In other words, the arrangement is such that the pin 35 will not move away from that edge of the slot 34 95 against which the pin is working.

The device described and shown operates as follows: Before a record is placed on the turn-table 3, the latter would be held against rotation by the arm 13 engaging the same, the parts being in the positions shown in 100 Fig. 3. To play a record, such as 4, which may for the sake of illustration be of the twelve inch type, the same is placed on the turn-table, and the reproducer 6 turned to bring the stylus or needle 7 into playing position, as usual. Before the needle is placed on the record, the reproducer is moved out beyond the turn-table. As the pin 26 is at that end of the slot 27 as shown in Fig. 3, the arm 24 is held against further movement in that direction. The arm 31 may, however, be swung with respect to the arm 24 in a direction permitting the pin 35 to be moved to the outer end of the slot 34, and when this has occurred the reproducer will 115 reach the position shown by the dot-and-dash lines A in Fig. 3. During this movement of the tone arm 5, the turn-table is held against rotation by the arm 13, as shown in said Fig. 3. After the reproducer 120 has reached this position, it is swung inward over the record 4, and in so doing the arms 24 and 31 move as one until the pin 26 reaches the opposite end of the slot 27. During this movement, the arm 24 swings 125 the plate 10 in a direction to throw the arm 13 out of engagement with the turn-table 3. This causes the rear end 16 of said plate to operate against the roller 22, compressing the spring 23, and brings the roller into con- 130

tact with the end edge 19 of said plate. The reproducer at that time would be over the record, say about the position as shown in dotted lines in Figs. 3 and 6, and the turn-table would be rotated by the spindle 2. As the reproducer is swung inward toward the center of the record, the arms 24 and 31 move as a unit until the pin 26 has about reached the end of the slot 27 at the arm 13. At that time, the reproducer has not as yet reached the end of the playing groove and the plate 10 has been swung to a position where the roller 22 will be projected forward and ride up the inclined edge 17 and throw the arm 12 into engagement with the turn-table and stop the same, as shown in Fig. 1. The arm 24 now being held against further movement in that direction, a continued movement in that direction of the arm 31 is permitted to allow the stylus 7 of the reproducer to be brought to the end of the selection on the record and at a point where it is desired to effect an automatic stopping of the turn-table. This position is shown in Fig. 1. Thus the device has been set to stop the turn-table as soon as the playing of the selection has ceased. The tone arm is then swung outward to place the stylus 7 against the record at the beginning of the selection to play the same, and during such movement, the arms 24 and 31 again move as a unit toward the opposite end of the slot 27. In so doing, the arm 24 operates against the plate 10 and swings its arm 12 out of contact with the turn-table, as shown in Fig. 6, whereupon the turn-table will be rotated and the record played. As the needle or stylus 7 travels over the face of the record toward the inner end of the playing groove, the arms 24 and 31 will move as a unit and operate against the plate 10 to move it into a position causing the plunger 20 to throw the arm 12 into contact with the turn-table and automatically stop the same immediately after the playing of the selection has ceased. In other words, the turn-table is automatically stopped at the place where the device has been set to operate for that purpose. Should a record have a diameter greater or less than the one shown, and the end of the selection cease at the extreme end of the playing groove or at any point in advance of that end, the device may be set to automatically stop the turn-table as soon as the playing of the selection of that particular record has ceased, by first setting the device to stop at that point and then swing the tone arm into a position to start the record and place the stylus on the record at the beginning of the playing groove. Thus my device is capable of use with records of varying diameters and having selections ending at varying points from the extreme end of the playing groove. This is brought about by permitting the angular

relation between the arms 24 and 31 to be changed to meet the particular conditions presented by the particular record being played. The swinging movement of the arm 24 is the same at all times, that being determined by the length of the slot 27. Thus, should one record have its selection terminate substantially at the extreme end of the playing groove, the arm 31, in setting the device to stop at the end of that selection, would be moved to occupy a position at such an angle to the arm 24 that the plate 10 would not be swung into turn-table stopping position by the plunger 20 until the stylus completed the playing of that selection; while, on the other hand, should another record have its selection terminate more in advance of the end of the playing groove than in the first, the arm 31 would, in setting the device to stop the turn-table at the end of that selection, be moved to a position to occupy a different angle to the arm 24 and effect a stopping of the turn-table when the end of that selection had been reached. Thus it will be seen that my device may be set to stop the turn-table at the end of the selection of any record to be played, and, furthermore, may stop the turn-table before the end of the selection is reached if that is desired. No matter at what point the turn-table is to be stopped automatically, the structure is such that the turn-table will be started automatically by swinging the tone arm into playing position after the device has been set to stop the turn-table at a given point.

With my device applied to a machine, it is apparent that the turn-table will be automatically stopped and automatically started by merely manipulating the tone arm and thus it is unnecessary to operate separate or independent parts to accomplish this result. Moreover, the turn-table will be started as soon as the tone arm is swung into position to place the stylus on the record, thus avoiding the possibility of accidentally or prematurely actuating the stopping device to effect the stopping of the record before intended. Then again, the structure is such that it may be applied to phonographs of different makes, and is simple and inexpensive in its construction and operation. The plunger 20 acts quickly to effect a starting or stopping of the turn-table at the moment required, thus producing a quick acting device.

In Fig. 8, the arms 24 and 31 are shown in full lines at one end of the slot 27, and in dotted lines to indicate that such parts move as a unit when being swung away from that end of the slot. In Fig. 9, the same arms are shown in full lines at the opposite end of the slot, and the dotted lines indicate how the arm 31 may be moved relatively to the arm 24 when the latter is held against rotation.

In Fig. 11, I have shown a form of con-

struction whereby the stopping of the turn-table at the inner end of the record may be brought about gradually so that the turn-table is not stopped with a jerk, and thus 5
5 avoid digging the stylus or needle into the record. As shown, the rear extension 16 of the pivoted plate 10 has an end edge 44 curved from the inclined side edge 18 to a distance and to such an extent that the plunger 20 operates to increase the pressure of 10
10 the arm 12 on the turn-table after the arm has been initially moved into contact therewith. The edge 44 in being curved gradually away from the inclined side edge 18, 15
15 permits the roller 22 to ride directly forward on said curved edge 44 after the arm 12 has been moved into contact with the turn-table, and as the movement of the plate 10 in that direction is continued by the action of the 20
20 arms 24 and 31, the spring 23 continues to force the plunger 20 forward, and the pressure of the arm 12 on the turn-table is increased so that the turn-table is brought to a stop gradually and without jerking. 25
25 When such feature of construction is employed, the inclined side edge 17, as shown in the preceding figures, is omitted.

While I have shown and described in detail a device embodying the features of my 30
30 invention, it is to be of course understood that the details of construction and arrangement of parts may be variously changed and modified without departing from the spirit and scope of my invention.

35 I claim as my invention:

1. In a phonograph, the combination of a 40
40 turn-table, a tone arm mounted to swing over said turn-table and provided with a reproducer, and mechanism for automatically starting and stopping said turn-table, comprising two stop members movable alternately into engagement with the turn-table for stopping the same, and means actuated upon the swinging of the tone arm and reproducer into predetermined positions to cause 45
45 said stop members to be moved alternately into engagement with said turn-table, and to move and hold said stop members out of engagement with the turn-table during the 50
50 movement of the tone arm between those positions.

2. In a phonograph, the combination of a 55
55 turn-table, a tone arm mounted to swing over said turn-table and provided with a reproducer, and mechanism for automatically starting and stopping said turn-table, comprising a pivotally mounted plate having two stop members, means acting against said plate for swinging said stop members alternately into engagement with the turn-table for stopping the same, upon the swinging of the tone arm and reproducer into certain 60
60 predetermined positions and for holding said stop members out of engagement with said turn-table during the movement of the tone 65
65

arm between those points, and coacting means between said plate and tone arm for swinging said plate by the movement of said tone arm.

3. In a phonograph, the combination of 70
70 a turn-table, a tone arm mounted to swing over said turn-table and provided with a reproducer, and mechanism for automatically starting and stopping said turn-table, comprising a pivoted plate having two stop 75
75 members and an extension, means operating against said extension to swing said plate and move said stop members alternately into engagement with the turn-table for stopping the same, when the tone arm and reproducer 80
80 have been swung into certain predetermined positions, and to hold said stop members out of engagement with said turn-table during the movement of the tone arm between those positions, and a pivoted arm having one end 85
85 coacting with said plate to swing the same, and the other end connected with said tone arm for moving said pivoted arm upon the swinging of said tone arm.

4. In a phonograph, the combination of 90
90 a turn-table, a tone arm mounted to swing over said turn-table and provided with a reproducer, and mechanism for automatically starting and stopping said turn-table, comprising a pivoted plate having two arms and 95
95 an extension, the latter having inclined side edges and a curved edge therebetween, means operating against said extension and when engaged with said inclined side edges to swing said arms alternately into engagement with said turn-table for stopping the same, and for holding said arms out of engagement with said turn-table when engaging the curved edge of said extension, and coacting means between said plate and tone 100
100 arm for moving said plate upon the swinging of said tone arm.

5. In a phonograph, the combination of a 110
110 turn-table, a tone arm mounted to swing over said turn-table and provided with a reproducer, and mechanism for automatically starting and stopping said turn-table, comprising a pivotally mounted plate having two arms and an extension, the latter having inclined side edges and a curved edge 115
115 therebetween, a spring pressed plunger carrying a roller acting against said side edges to swing said arms alternately into engagement with said turn-table for stopping the same, and for holding said arms out of engagement with said turn-table when engaging said curved edge, and two pivoted arms frictionally engaged, with one coacting with said plate to swing the same and the other having a pin and slot connection with said 120
120 tone arm.

6. In a phonograph, the combination of a 125
125 turn-table, a tone arm mounted to swing over said turn-table and provided with a reproducer, and mechanism for automatically 130
130

starting and stopping said turn-table, comprising a pivoted plate having two arms and an extension, the latter having an inclined edge and a curved edge, means operating 5 against said extension for alternately swinging said arms into engagement with said turn-table for stopping the same, and acting when engaging said inclined edge to swing one arm quickly into engagement with said 10 turn-table, and when acting against said curved edge to gradually increase the pressure of the other arm against said turn-table, and coacting means between said plate and tone arm for moving said plate upon the 15 swinging of said tone arm.

7. In a phonograph, the combination of a turn-table, a tone arm mounted to swing over said turn-table and provided with a reproducer, and mechanism for automatically 20 starting and stopping said turn-table, comprising a pivoted plate having two stop members, means acting against said plate for swinging said stop members alternately into engagement with said turn-table for 25 stopping the same and for holding said stop members out of engagement with said turn-table during a portion of the swinging movement of said tone arm, a pivoted arm coacting with said plate for swinging the same, 30 a second pivoted arm frictionally connected with said first arm, said second arm having an elongated slot arranged at an angle to the length thereof, and a pin carried by the tone arm and extending into said slot.

35 8. In a phonograph, the combination of a turn-table, a tone arm mounted to swing over said turn-table and provided with a reproducer, and mechanism for automatically starting and stopping said turn-table, 40 comprising a pivoted plate having two stop members, means acting against said plate for swinging said stop members alternately into engagement with said turn-table for stopping the same and for holding said stop 45 members out of engagement with said turn-table during a portion of the swinging movement of said tone arm, a pivoted arm coacting with said plate for swinging the same,

a second pivoted arm frictionally connected with said first arm, said second arm having 50 an elongated slot arranged at an angle to the length thereof, a band clamped about said tone arm, and a pin secured to said band and extending into said slot.

9. A device for automatically starting and stopping the turn-table of a phonograph, comprising a base plate, a pivoted plate having two stop members, means for swinging said stop members alternately into turn-table engaging position, a pivoted arm having one end extending into a notch in said plate for swinging said stop members out of turn-table engaging position, a pin secured to said arm and extending into an arcuate slot in said base plate, a second pivoted arm 65 frictionally connected with said first arm and having an elongated slot arranged at an angle to the length of said arm, and a clamp ring provided with a pin to engage in said slot.

70 10. A device for automatically starting and stopping the turn-table of a phonograph, comprising a base plate, a pivoted plate having two stop members, means for swinging said stop members alternately into 75 turn-table engaging position, a pivoted arm having one end extending into a notch in said plate for swinging said stop members out of turn-table engaging position, a pin secured to said arm and extending into an 80 arcuate slot in said base plate, an upright sleeve rigidly secured to the pivoted end of said arm and having a conical portion above the same, a second arm having one end split and provided with a conical hole to receive 85 the conical portion of said sleeve, clamp nuts for holding said second arm on said sleeve, said second arm having an elongated slot arranged at an angle to the length thereof, and a slip clamp ring provided with a pin to 90 engage in said slot.

In testimony that I claim the foregoing as my invention, I affix my signature this 22nd day of December, A. D. 1919.

JOHN A. EITUTIS.
